US00D917576S

(12) **United States Design Patent** (10) Patent No.: **US D917,576 S**
Matteo (45) Date of Patent: **** Apr. 27, 2021**

(54) **MOTOR AND PUMP SHROUD FOR AIR COMPRESSOR**

(71) Applicant: **Harbor Freight Tools USA, Inc.**,
Calabasas, CA (US)

(72) Inventor: **Michael Matteo**, Los Angeles, CA (US)

(73) Assignee: **Harbor Freight Tools USA, INC.**,
Calabasas, CA (US)

(**) Term: **15 Years**

(21) Appl. No.: **29/704,532**

(22) Filed: **Sep. 5, 2019**

(51) LOC (13) Cl. **15-02**

(52) U.S. Cl.

USPC **D15/9; D15/7**

(57) **CLAIM**

The ornamental design for an motor and pump shroud for air compressor, as shown and described.

DESCRIPTION

FIG. 1 is a top-front perspective view of an motor and pump shroud for air compressor showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom-rear perspective view thereof.

The dashed broken lines in the figures illustrate portions of the motor and pump shroud for air compressor that form no part of the claimed design.

1 Claim, 8 Drawing Sheets
